UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

TRACKER-BOARD AND MUSIC-SHEET.

1,206,779.

Specification of Letters Patent. Patented Nov. 28, 1916.

Application filed April 8, 1910. Serial No. 554,142.

To all whom it may concern:

Be it known that I, PAUL BROWN KLUGH, a citizen of the United States, residing at Chicago, in the county of Cook and State 5 of Illinois, have invented a certain new and useful Improvement in Tracker-Boards and Music-Sheets, of which the following is a full, clear, concise, and exact description, reference being had to the accompanying 10 drawings, forming a part of this specification.

My invention relates to mechanical musical instruments, and especially to instruments 15 commonly known as player pianos or piano players.

The invention relates more in particular to the tracker board and music sheet arrangement of such instruments, and involves a construction of tracker board and music 20 sheet employed in mechanical musical instruments for producing solo effects.

The tracker board in question is provided with two sets or series of apertures, one of 25 which may be the usual set of tracker board apertures and the other of which is composed of narrow slots or slits, each arranged at one side and in the rear of one of the apertures of the first-mentioned or usual set of apertures. The music sheet to be used 30 with a tracker board of this character is preferably provided with two different styles of perforations, the perforations of one style being comparatively narrow and may be of the usual width of music sheet 35 perforations, and the perforations of the other style being of greater width than those of the first mentioned style. The narrow perforations are of such width as to register with and uncover the tracker board apertures of one set,—that is, the usual set,—but not to open or uncover the supplemental apertures. The other or wide perforations 40 of the music sheet are of such width as to uncover both the usual apertures and the supplemental apertures. The supplemental apertures, being in the rear of the usual 45 apertures, are uncovered or opened first by the wide perforations.

The tracker board herein set forth and 50 claimed can be used for producing solo effects and also for other purposes.

In the accompanying drawings, Figure 1 is a front elevation of a tracker board and music sheet embodying my present inven-

tion; Fig. 2 is a front elevation of a portion 55 of the tracker board; Fig. 3 is a sectional view taken on the line 3—3 in Fig. 2.

In the drawings, the tracker board is represented at 1 and the music sheet at 2. The tracker board is provided with a series of 60 apertures 3, 3 which may be of any convenient shape, but are preferably round, as shown in Fig. 2. The tracker board is also provided with a second or supplemental series of apertures 4, 4 which are at one side 65 and in the rear of the apertures 3, 3 and are preferably in the form of long narrow slots or slits.

The music sheet 2 is provided with perforations 5, 5 which may be of the usual or 70 ordinary width and, as such, are capable of opening the apertures 3, 3 of the tracker but incapable of opening the supplemental apertures 4, 4 because they are not sufficiently wide to uncover said supplemental apertures. The music sheet is also provided 75 with other perforations 6, 6 of greater width than the perforations 5, 5, each sufficiently wide to open both an ordinary aperture 3 and its associated aperture 4, as shown in 80 Fig. 1. As the music sheet advances in the direction of the arrow in Fig. 1, the narrow or usual perforations 5, 5 will open the tracker apertures 3, 3 in the usual way, and the wide perforations 6, 6 will first open 85 the apertures 4, 4 with which they register and then open the associated apertures 3, 3.

In Fig. 3, I have shown two series of tubes, 7, 7 and 8, 8 for the apertures 3, 3 and two series of tubes, 9, 9 and 10, 10, for 90 the supplemental apertures 4, 4. The tubes 8, 8 are bent down and the tubes 10, 10 are bent up, whereas the tubes 7, 7 and 9, 9 extend straight back, the result of which is that the pneumatic connections for the 95 tracker can be readily and easily made. It will be seen that the music sheet has two kinds or styles of perforations, both of which are so aligned as to track with the usual set of apertures in a tracker board, and it will 100 also be seen that the tracker board has its supplemental apertures arranged in the rear of and entirely out of alignment with the usual apertures,—by "entirely out of alignment" being meant that the supplemental 105 apertures are at one side of the usual apertures so that no part of any aperture is in alignment with another with regard to the

direction of travel of the music sheet. It will also be seen that the narrow perforations of the music sheet open the usual tracker board apertures only, whereas the wide perforations open both the usual and associated supplemental apertures.

What I claim as my invention is:

1. The combination of a tracker having the usual set of apertures and also having supplemental apertures consisting of long narrow slots or slits located in the rear of and entirely out of alignment with the usual apertures, and a music sheet having narrow and wide perforations arranged to register with the tracker apertures, whereof the narrow perforations open only one aperture of a pair and the wide perforations open both apertures of the same.
2. A tracker having two sets of apertures arranged in pairs, each pair consisting of one front and one rear aperture only, one aperture of each pair being in front of the other and offset therefrom longitudinally of the tracker, the apertures of the front set being circular and on the same side of the corresponding apertures of the rear set and the apertures of the rear set being elongated transversely of the tracker.
3. A tracker having two sets of apertures arranged in pairs, each pair consisting of one front and one rear aperture only, one aperture of each pair being in front of the other and offset therefrom, the apertures of the front set being circular and on the same side of the corresponding apertures of the rear set and the apertures of the rear set being elongated at and near the top surface

of the tracker but circular throughout the remainder of their extent.

4. A tracker having two sets of apertures arranged in pairs, each pair consisting of one front and one rear aperture only, one aperture of each pair being in front of the other and offset therefrom longitudinally of the tracker, the offset of all the front apertures being on the same side of the corresponding apertures of the rear set and the apertures of the rear set being elongated transversely of the tracker.

5. A tracker having front and rear series of apertures arranged in pairs with a front and a rear aperture in each pair, each aperture of the front series being paired with an aperture of the rear series and offset therefrom longitudinally of the tracker and the rear apertures being elongated transversely of the tracker.

6. A tracker having front and rear series of apertures arranged in pairs with a front and a rear aperture in each pair, the rear apertures being offset longitudinally of the tracker with reference to the corresponding front apertures, all of said rear apertures being offset at the same side of the front apertures and said rear apertures being of substantially greater length but of less width than the front apertures.

In witness whereof, I hereunto subscribe my name this 2nd day of April A. D., 1910.

PAUL BROWN KLUGH.
